COMBINED ELECTRIC HEATER AND MAGNETIC STIRRER

Alexander I. Newman, River Forest, Ill., assignor to Lab-Line Instruments, Inc., Melrose Park, Ill., a corporation of Delaware

Filed Apr. 1, 1966, Ser. No. 1,734

Term of patent 14 years

(Cl. D16—2)

FIG. 1

FIG. 2

FIG. 1 is a perspective view of a combined electric heater and magnetic stirrer embodying my new design. FIG. 2 is a side elevational view thereof, the opposite side having the same appearance.

The rear is unornamented.

I claim:

The ornamental design for a combined electric heater and magnetic stirrer, as shown and described.
